UNITED STATES PATENT OFFICE.

ERNEST E. LLOYD, OF MISSOULA, MONTANA.

WAGON-SEAT.

1,132,948.

Specification of Letters Patent. Patented Mar. 23, 1915.

Application filed March 18, 1914. Serial No. 825,612.

To all whom it may concern:

Be it known that I, ERNEST E. LLOYD, a citizen of the United States, residing at Missoula, in the county of Missoula and 5 State of Montana, have invented certain new and useful Improvements in Wagon- Seats; and I do hereby declare the following to be a full, clear, and exact description of the invention, such as will enable others 10 skilled in the art to which it appertains to make and use the same.

This invention relates to seats for wagons and other similar vehicles; and it consists in the novel construction and combination 15 of the parts hereinafter fully described and claimed whereby the seat may be clamped to the body of the vehicle in various positions.

In the drawings, Figure 1 is a side view of 20 a portion of a wagon body provided with a seat according to this invention. Fig. 2 is a detail end view of one of the clamping devices. Fig. 3 is a plan view of the same.

The body or box 2 is of any approved construction, and 3 is the seat which is supported by springs 4 above two seat bars 5. The seat bars have hooks 6 which project laterally from them and engage with the 25 sides of the body or box 2.

In order to prevent the seat bars from 30 sliding and tilting out of place, a clamping plate 16 is secured to each seat bar above the lower portion of the spring which is bolted to it. This clamping plate has a 35 socket 7 on its upper side and a slot 8. A clamping bolt 9 is slidable in the socket 7 and has a projecting rib 10 which engages with the slot 8 so that the bolt is prevented

from revolving. The bolt has a thumb-nut 12 at one end for tightening it, and at its 40 other end it has a downwardly projecting clamping member 14. A clamping member 15 is secured to the side of the seat bar opposite the clamping member 14, and both clamping members preferably have convex 45 faces which engage with the side of the box which comes between them.

The seat can be slid longitudinally of the box to any desired position, and is clamped by means of the nuts 12, so that the seat 50 cannot slide or tilt out of place.

What I claim is:

The combination, with a vehicle body provided with a side, of a seat, a seat bar normally slidable on the said side, a leaf spring secured to the seat and bearing on the seat bar, a clamping plate secured to the seat bar over the lower part of the spring and provided with a socket, a non-revolute clamping bolt slidable longitudinally in the said 60 socket and having at one end a downwardly projecting clamping member provided with a convex face which bears against the outer surface of the body side, a clamping member secured to the seat bar and provided 65 with a convex face which bears against the inner surface of the body side, and means for operating the clamping bolt to secure and release the seat.

In testimony whereof I have affixed my 70 signature in the presence of two witnesses.

ERNEST E. LLOYD.
